LIQUID FUSE

Ralph H. Earle, Wauwatosa, and Walter E. Mitzelstadt, Kenosha, Wis., assignors to Line Material Company, South Milwaukee, Wis.

Application May 5, 1932, Serial No. 609,453

11 Claims. (Cl. 200—120)

This invention relates to liquid fuses.

In liquid fuses it is the customary practice to provide a tube of glass, or other insulating material, within which an arc extinguishing liquid is carried. An upper and a lower contact are provided, connected by a fuse link and a flexible cable, a spring being employed to draw the lower portion of the fuse downwardly when the fuse blows. These liquid fuses frequently give considerable trouble due to the sudden evolution of gases producing a quickly applied gas pressure which, under short circuit or excessive load conditions, may break the glass tube. Another serious defect of these devices is that when the fuse is ruptured, an arc is established which frequently plays about and damages the upper contact, often cracking and breaking the glass.

This invention is designed to overcome the above noted defects and objects of this invention are to provide a novel form of liquid fuse which will prevent arcing to the upper contact, which greatly lengthens the path of the arc, which introduces a "hairpin" turn in the path of the arc, which protects the glass or insulating tube, which protects the upper contact, and which shoots the products of combustion far away from the fuse contacts.

In greater detail, further objects are to provide a liquid fuse having a main or stationary insulating tube of glass or other suitable material, and a movable insulating tube of fiber or other insulating material which is initially housed within the glass tube and automatically moves upwardly when the fuse blows and projects from the glass tube and from the upper contact, and which thus substantially instantly greatly elongates the path which an arc would have to follow and at the same time forms a vent tube which projects the products of combustion far away from the fuse contacts.

Further objects are to provide a construction which may be applied to standard types of liquid fuses without alteration, which does not necessitate an increase in the overall dimensions of the fuse, which is cheap and easy to produce, and which is easy to re-fuse, the parts of the liquid fuse being protected against damage as heretofore explained, thereby allowing the device to be used over and over again.

Embodiments of the invention are shown in the accompanying drawing, in which:

Figure 1 is a vertical sectional view showing the fuse in its initial position.

Figure 2 is a corresponding view (somewhat

shortened up) showing the fuse after it has blown.

Figure 3 is a sectional view on the line 3—3 of Figure 2.

Figure 4 is a fragmentary view of a modified form of the invention.

Referring to Figures 1, 2 and 3 it will be seen that the fuse comprises an insulating tube 1 of glass or other suitable material provided with a lower contact 2 and an upper contact 3. A fuse link of any suitable form indicated generally by the reference character 4 is provided adjacent the upper contact and is supported in any suitable manner as by means of the toggle-shaped spring supporting bridge member 5 resting in notches 6 formed in a split ferrule or ring 7. The ring 7 fits within the upper portion of the upper contact 3 and rests against the shouldered portion 8 formed thereon. The toggle action of the bridge member 5 forces the ends of the bridge member against the two halves of the split ring 7, and thus forces the two halves of the split ring 7 downwardly and outwardly into firm contact with the upper contact 3, thereby securing an excellent electrical connection between both the halves of the split ring and the upper contact 3 and between the ring and the ends of the bridge member 5 or the ends of the fuse wrapped thereon.

The lower end of the fuse link is detachably secured to a connector or clip 9 firmly attached to the upper end of a helical spring 10 and to a flexible conducting cable or leader 11. The lower end of the spring 10 and leader or cable 11 are connected in any suitable manner to the lower contact 2. If desired, the intermediate portion 35 of the fuse link may be covered by a cork or other similar member 12 in a well known manner, and it is also preferable, in accordance with the usual construction, to provide a reduced portion (not shown) in the fuse link at that portion thereof 40 covered by the cork 12.

The upper contact is a ring-like member and is closed by an easily rupturable diaphragm 13 preferably of some soft alloy or of a similar material. The diaphragm 13 is held in place by a ring nut 14, and when the fuse is blown, the diaphragm is torn around its edges and blown free from the fuse. It is preferable to provide a protecting disc or shield 15 over the upper end of the ring nut 14 to thereby guard the diaphragm 13, such disc being provided with spring fingers 16 clipped below the bottom edge of the ring nut 14 or held thereto in any other suitable manner.

It is to be noted that the split ferrule 7 is provided with an inwardly projecting lower flange 17 55

which loosely surrounds the reduced portion 13 of an insulating tube 19 of fiber or other suitable material. This fiber tube is freely slideable upwardly through the ferrule 7, or ring, and is prevented from dropping downwardly beyond its position shown in Figure 1 by means of an upper collar or upper shoulder 20, preferably integrally formed thereon.

A second and lower shoulder 21 is formed at a point spaced downwardly from the upper shoulder 20, as clearly shown in Figures 1 and 2, to limit the upward motion of the fiber tube 19. The fiber tube has an unobstructed central bore which provides a relatively large internal space within which the upper end of the spring 16 and the major portion of the fuse link are positioned.

The apparatus is filled with an arc extinguishing liquid to approximately the level indicated by the reference character 22. Such liquid is carbon tetrachloride or any other suitable material.

It is to be noted that the split ring or ferrule 7 enables the fiber tube to be formed as an integral structure by merely reducing an intermediate portion thereof. The split ring is thereafter positioned about the fiber tube and this structure is slipped into position within the main tube or fuse body.

The operation of the device is wholly automatic and is as follows:

When the fuse blows, the outwardly rushing products of combustion burst the rupturable diaphragm 13 and blow the central portion of the diaphragm, and the disc 15 away from the fuse. At the same time the fiber tube or sleeve 19 is suddenly and substantially instantaneously projected upwardly into the position shown in Figure 2. Any arc formed by the rupturing of the fuse cannot, therefore, pass to the upper contact as it has first to pass through the projected fiber tube 19 in the position shown in Figure 2, make a "hairpin" turn at the upper edge of the fiber tube and loop backwardly to the upper contact.

This construction, therefore, provided a relatively greatly increased length of travel for any arc that can be formed and in reality prevents the formation of such arc.

It is to be noted at this point that as the fiber tube moves upwardly, the supporting member 5 for the fuse slides upwardly still in contact with the metal ferrule 7 and any arc that is formed exists between the ruptured portions of the fuse link located within the fiber tube. This entire structure substantially instantly moves upwardly and thereby prevents the formation of an arc from the lower segment of the fuse link to the upper contact.

In addition to the operation thus far described, the projected fiber tube shoots the products of combustion far away from the contacts of the fuse. These products of combustion include the highly heated gases which when at their extremely high temperature tend to form a conducting medium.

Instead of this, these products of combustion, as stated, are projected from the fuse at a point remote from the upper contact and thus the formation of an arc from this cause is prevented.

Another important result produced by this construction is that there is no chance of the arc's striking the glass tube, thus preventing the cracking of the glass tube.

The construction also provides for the immediate relief of the pressure gases and thereby protects the structure from rupture due to a sudden excessive rise in pressure. Instead of this a freely

vented means is provided which also secures the above enumerated results.

Actual tests of this apparatus have proven highly successful and it has been found that even under short circuit conditions that the fuse is highly reliable and produces remarkably good results.

Due to the fact that there is no burning of the upper contact and no cracking or breaking of the glass, it will be seen that the device can be used over and over again. Also, due to the simple construction and the unobstructed manner in which the apparatus is formed, re-fusing is very easy.

The invention may take other forms, one of which is shown in Figure 4. In this form of the invention the same construction is followed with the exception that the fiber tube 19' is provided with a tapered portion 23 which wedges within the inwardly projecting flange 17 of the metal ferrule or split ring 7.

It will be seen that the device is very simple in construction, that it may be cheaply made, that it is applicable to standard types of fuse structures, and that it is reliable in operation.

Although this invention has been described in considerable detail, it is to be understood that such description is intended as illustrative rather than limiting, as the invention may be variously embodied and is to be interpreted as claimed.

We claim:

1. A liquid fuse comprising a main tube including contacts at opposite ends and adapted to contain an arc extinguishing liquid, a fuse link located wholly within said main tube, a sleeve having a relatively large internal bore compared with the internal bore of said main tube, said sleeve being slidably carried wholly within said main tube and adapted to be projected outwardly therefrom when said fuse blows, said sleeve being normally spaced from both ends of said main tube, and means for arresting the outward motion of said sleeve by an interlocking action between said sleeve and said main tube.

2. A liquid fuse comprising a main tube adapted to contain an arc extinguishing liquid and having an annular upper contact and a lower contact and having a closed lower end, a sleeve slidably mounted within said main tube and freely open at both ends and adapted to be projected outwardly through said annular contact when said fuse blows, said sleeve and said main tube having interlocking portions to limit the outward projection of said sleeve, said sleeve having a relatively large bore compared with that of the main tube and providing a relatively unobstructed passageway for the free discharge of gases, and a fuse link extending completely through said sleeve and located within said main tube and electrically connecting said contacts.

3. A fuse comprising a main tube having a contact closing one end thereof and having an annular contact adjacent the other end thereof, a fuse link located within said main tube and electrically connected to said contacts, and an insulating sleeve normally wholly housed within said main tube below the upper end of said annular contact and projectable outwardly into a position protecting said annular contact and projecting beyond the upper end of said annular contact, said sleeve being freely open at both ends, said sleeve and said main tube having interlocking portions to arrest the outward motion of said sleeve after said sleeve has been projected

a material distance outwardly from said main tube.

4. A fuse comprising a main tube having a contact closing one end thereof and having an annular contact adjacent the other end thereof, a conductor including a fuse link located within said main tube and electrically connected to said contacts, and an insulating sleeve normally housed within said main tube below the upper end of said annular contact and projectable outwardly into a position protecting said annular contact and projecting beyond the upper end of said annular contact, said sleeve being a tube freely open at both ends and forming a conducting member for discharging gases above the upper end of said main tube and at a distance spaced therefrom after said fuse blows, said conductor normally extending completely through said sleeve, over the upper end of said sleeve to said annular contact, said sleeve and said main tube having interlocking means to arrest the outward motion of said sleeve.

5. A liquid fuse comprising a main tube adapted to contain an arc extinguishing liquid, an upper annular contact forming an extension of the upper end of said main tube, a lower contact closing the lower end of said main tube, conducting means electrically joining said contacts and located within said main tube, said conducting means including a fusible section located adjacent said upper annular contact, and a sleeve of insulating material slidably positioned wholly within said main tube and projectable upwardly through said annular upper contact, said sleeve having a relatively large bore with reference to the internal diameter of the main tube and being freely radially open at both ends, said sleeve and said main tube having interlocking means to arrest the outward motion of said sleeve, whereby said sleeve forms an extension of the main tube and conducts gases and spraying liquid away from said upper annular contact.

6. A liquid fuse comprising a main tube adapted to contain an arc extinguishing liquid, an upper annular contact forming an extension of the upper end of said main tube, a lower contact closing the lower end of said main tube, conducting means electrically joining said contacts and located within said main tube, said conducting means including a fusible section located adjacent said upper annular contact, a sleeve of insulating material slidably positioned within said main tube and projectable upwardly through said annular upper contact, said sleeve being freely open at both ends and forming a conducting extension for conducting gases and spraying liquid away from said upper contact, and means for arresting the upward motion of said sleeve with the upper end of said sleeve positioned above the upper annular contact.

7. A liquid fuse comprising a main tube adapted to contain an arc extinguishing liquid, an upper annular contact adjacent the upper end of said main tube and forming an extension of the main tube, a lower contact adjacent the lower end of said main tube, conducting means electrically joining said contacts and located wholly within said main tube, said conducting means including a fusible section located adjacent said upper annular contact, a sleeve of insulating material slidably positioned within said main tube and having means for normally suspending said sleeve be-

low the upper end of said annular contact, said sleeve being adapted to move outwardly when said fuse blows with a material portion of said sleeve projecting upwardly beyond the upper end of said annular contact, said sleeve having a relatively large bore as compared with the diameter of the main tube and being freely open at both ends and forming an extension of said main tube for conducting discharged material therefrom when said fuse blows, and means for arresting the upward motion of said sleeve to determine its final position.

8. A liquid fuse comprising a main tube, an annular contact adjacent the upper end of said main tube having an annular flange, a slidable insulating tube having a reduced portion passing through said flange and having an enlarged lower portion for contacting with said annular flange to limit the outward motion of said sleeve upon blowing of said fuse, a lower contact carried by said main tube, and conducting means located within said main tube, electrically connecting said contacts, and passing through said sleeve.

9. A liquid fuse comprising a main tube an annular upper contact carrying an inwardly projecting flange located adjacent the upper end of said main tube, an insulating sleeve having a reduced portion passing through said annular flange and having an upper shoulder normally resting upon said flange, said sleeve being slideable outwardly through said flange, and having means for arresting the outward sliding motion when said sleeve projects beyond the upper end of said annular contact, and conducting means including a fuse link, said conducting means electrically joining said contact and passing through said sleeve.

10. A liquid fuse comprising a main tube, a lower contact closing the lower end of said main tube, an upper annular contact having a shoulder therein, a split ferrule resting upon said shoulder and having an inwardly projecting annular flange, an insulating tube slidably passing through said flange and having an upper shoulder normally resting upon said flange, said tube being slideable through said flange to a position where it projects beyond the upper end of said annular contact, means for arresting the upward motion of said insulating tube to determine its final position after the fuse has operated, and a fuse link electrically connected to said contacts and located within said sleeve.

11. A liquid fuse comprising a main tube, a lower contact closing the lower end of said main tube, an upper annular contact having a shoulder therein, a split ferrule resting upon said shoulder and having an inwardly projecting annular flange, an insulating tube slidably passing through said flange and having an upper shoulder normally resting upon said flange, said tube being slideable through said flange to a position where it projects beyond the upper end of said annular contact, means for arresting the upward motion of said insulating tube to determine its final position after the fuse has operated, a fuse link electrically connected to said contacts and located within said sleeve, and a rupturable diaphragm normally closing said annular upper contact and located above the upper end of said insulating tube.
